UNITED STATES PATENT OFFICE.

ARTHUR MARGO, OF NANTES, FRANCE.

FURNACE FOR BURNING FACTORY REFUSE.

1,390,304.

Specification of Letters Patent. Patented Sept. 13, 1921.

Application filed March 31, 1919. Serial No. 236,612.

(GRANTED UNDER THE PROVISIONS OF THE ACT OF MARCH 3, 1921, 41 STAT. L., 1313.)

To all whom it may concern:

Be it known that I, ARTHUR MARGO, a citizen of the Republic of France, residing in Nantes, Loire-Inférieure, France, have invented certain new and useful Improvements in Furnaces for Burning Factory Refuse, for which I have filed an application in France, November 30, 1916, Patent No. 486,564, and of which the following is

10 a specification.

This invention relates to a combined furnace which is particularly adapted for burning waste or refuse of various kinds, such as shavings, sawdust, bagasse, waste of spinning mills and sawmills, turf, and other kinds of refuse.

The improved furnace may be used with advantage for heating steam boilers of practically any kind, for instance elephant boilers, semi-tubular, multi-tubular and other boilers, and may be arranged either underground, or as an internal furnace (being in the latter case mounted upon a suitable carriage). The improved furnace comprises 20 a feeding chute or hopper which is separated from the furnace by a movable shutter or feed regulator the opening of which may be adjusted by means of a counter-weighted lever adapted to move upon a graduated 25 scale. The waste or refuse forming the fuel descends from the hopper or chute and burns upon a stepped grate at the bottom of which is disposed a tilting clinker grate.

At the lower portion of the front plate of 30 the furnace are arranged pivoted regulating shutters for controlling the admission of air. These shutters or regulators are operated by means of a counter-weighted lever adapted to be fixed in any desired position upon a 35 graduated scale.

A steam boiler furnace constructed according to the invention is shown by way of example in the accompanying drawings, in which Figure 1 is a front view, and Fig. 2 40 a longitudinal section.

For the purpose of building in the improved furnace, the lower portion of the front metal frame of the boiler may be substituted by a special front plate 1, the latter 50 being secured to an upper plate 2 of usual construction. The plate 1 is provided with an upper opening 3 for the supply of the fuel and one or two lower openings 4 for

the device for regulating the admission of air to the grate. 55

In front of the opening 3 there is arranged a feeding chute or hopper 5 in which are placed by means of a shovel or otherwise the waste products to be burned, which when the movable shutter 7 is opened slide down 60 upon the stepped grate 6. The shutter or regulator 7 is provided with a shield 8 protecting it against the back flame, and is fast upon a shaft 9 mounted in bearing 10 and adapted to be operated by a counter-weighted lever 11 which if continuous feeding is adopted may be fixed in any desired position upon the graduated sector 12. The stepped grate 6 consists of flat bars as shown in the drawings so as to prevent effectively the 70 fuel from dropping through into the ashpit, and is prolonged at the lower end by a tilting clinker grate 13. In order to prevent the back flame from passing outside at the upper end of the regulator 7, the shaft 9 75 is covered in front by a metallic shield 14 (see Fig. 2). Underneath the feeding chute or hopper 5 are arranged within openings 4, regulating shutters 15 which are mounted upon the shaft 16 and serve to control the 80 admission of the air necessary for the combustion. These shutters 15 may be operated by means of a counterweighted lever 17 which may be fixed in any desired position upon a graduated sector 18. 85

If the fuel is fed into the chute or hopper 5 intermittently, by means of a shovel or otherwise, the attendant after filling the chute, operates the lever 11 so as to completely open the shutter 7, whereupon the 90 full charge instantly leaves the hopper and descends upon the stepped grate 6. Upon the lever 11 being then released, the opening 3 is automatically closed by the shutter 7. If on the other hand the furnace is to be 95 worked in such a manner that the grate is to be charged continuously from the chute, an elevator, for instance a bucket elevator, or any other suitable device may be used for feeding the fuel into the hopper 5. In this 100 case the opening of the shutter 7 is adjusted by means of the lever 11 and the graduated sector 12 in such a manner as to allow only the required quantity of fuel to pass continuously into the grate. 105

The clinker grate 13 may be manipulated

by means of a lever 19 mounted upon the front plate and connected by a rod 20 to an arm 21 upon the shaft of the grate 13.

I claim:—

5. 1. A furnace for burning waste products, comprising in combination a stepped grate having flat bars, a feeding chute arranged outside the furnace, a pivoted vertically-movable shutter separating the feeding chute from the furnace, a counter-weighted lever to operate the movable shutter, a graduated sector enabling the shutter to be maintained so as to give any desired opening, a shield for preventing the flames of the furnace 10 from entering the feed chute, and two lower pivoted shutters to regulate the entrance of air under the furnace.
15. 2. A furnace for burning waste products comprising in combination a stepped grate

having flat bars, a feeding chute arranged outside the furnace, a pivoted vertically-movable shutter separating the feeding chute from the furnace, a counter-weighted lever to operate the movable shutter, a graduated sector enabling the shutter to be maintained 25 so as to give any desired opening, a protecting shield placed above the pivot of the vertical shutter, two pivoted lower shutters to regulate the entrance of air under the grate, and a graduated sector to hold said lower 30 shutters in any desired position.

In witness whereof, I have hereunto signed my name in the presence of two subscribing witnesses.

ARTHUR MARGO.
